UNITED STATES PATENT OFFICE.

CHARLES H. MCNEIL, OF BEVERLY, MASSACHUSETTS.

WEIGHT-OPERATED CIRCUIT-CLOSER.

1,353,057.

Specification of Letters Patent. Patented Sept. 14, 1920.

Application filed July 21, 1919. Serial No. 312,121.

To all whom it may concern:

Be it known that I, CHARLES H. MCNEIL, a citizen of the United States, residing at Beverly, in the county of Essex and State 5 of Massachusetts, have invented new and useful Improvements in Weight-Operated Circuit-Closers, of which the following is a specification.

This invention has reference to an attachment 10 for baby carriages or cribs.

The primary object of the invention is to produce a simple, cheap and novel means for supporting a nursing bottle so that the same is conveniently held with respect to 15 the infant, and consequently the constant attendance of the nurse or mother during the feeding operation will not be necessitated.

It is a further object of the invention to 20 produce a bottle holding device wherein the bottle is yieldably supported and which is provided with means for sounding an alarm when the contents of the bottle are used, so that the same may be refilled and also so 25 that the infant can not suck in air from the empty bottle and become affected with colic.

Other objects and advantages will appear 30 as the nature of the invention is better understood, reference being had to the accompanying drawings, in which:

Figure 1 is an elevation illustrating the application of the improvement.

Fig. 2 is a top plan view thereof.

Fig. 3 is a sectional view approximately 35 on the line 3—3 of Fig. 1.

Fig. 4 is a sectional view approximately on the line 4—4 of Fig. 1.

Fig. 5 is a side elevation, parts being in 40 section and illustrating a modification.

Fig. 6 is an enlarged detail vertical sectional view of the milk bottle suspending device, the rod, yoke and slidable block being in elevation.

While in the accompanying drawings I 45 have illustrated my improvement in connection with a baby carriage, it is to be understood that the same is not to be thus restricted in its useful application, as the device may be attached to the crib of an infant.

On the horizontal stile 10 of one side of a 50 baby carriage I secure upper and lower plates 11 and 12 respectively. The upper plate is in the nature of the shade rod support for the carriage, a portion of the shade rod which is attached thereto being indicated by the numeral 13. The plates 11 and

12 are connected by screws 14, and consequently are removable. The upper plate 11 has a threaded opening therethrough, as may likewise the lower plate. The stile 10 60 is provided with an opening registering with the referred to openings, and if desired this last mentioned opening may be also threaded. Engaging in the threaded openings is the threaded end 15 of a vertically disposed rod 16. This rod has arranged thereon, outward of its threaded portion 15 an offset or laterally extending element 17 which is in the nature of a handle, so that the said rod may be easily and 70 quickly screwed on the support 10, or as quickly removed therefrom should occasion so require.

Arranged for slidable movement on the rod 16 is a block 18. Passing through a 75 threaded opening in one side of the block and contacting with the rod 16 is a thumb screw 19 which holds the block 18 adjusted on the rod 16. The block 18 has secured thereon a longitudinally disposed rod 20, 80 and the outer end of this rod is threaded. The horizontal rod 20 is not only susceptible to vertical adjustment with respect to the supporting rod 16, but the same may be turned to desired angles on the said supporting rod and clamped by the thumb screw 19. The outer end of the rod 16 has a hexagon brass nut 21 threaded thereon to prevent the block 18 from slipping off of the rod 20 in case the block 18 should get 90 loose.

On the rod 20 is a slidable block 22 having a threaded opening from the outer end thereof receiving a thumb screw 23 that contacts with the rod 20 and holds the block 22 95 adjustable on said rod. Swiveled to the under face of the block 22 by a headed element 24 is a yoke 25. Received in this yoke, and supported thereby is a ring 26. The ring 26 is provided with an opening that is surround by a boss 27. The boss has a threaded bore in which is received the threaded end of a tube 28.

Passing through the tube 28 is a rod 29 that also passes through the opening in the ring. 105 The rod 29 is the suspending element for the milk bottle and has its outer end formed with a hook 30. The hook is held against turning movement by being disposed beneath the arms provided in the bifurcated 110 end of a plate 31, the latter being integrally formed on a cap nut 32 which engages there-

with and which closes the lower end of the tube 28. Resting on the cap nut is a helical spring 33 that is, of course, arranged in the tube, and this spring contacts with a stud 5 or lug 34 on the rod 29 whereby to normally force the rod upwardly and one of the ends thereof into the ring 26. The hook 30 is designed to engage with the ring 35 on a cage 36 which supports the milk or feeding bottle 10 37, and by the arrangement as above described it will be seen that the bottle may be conveniently supported with respect to the infant in the crib or carriage. The bottle is likewise yieldably suspended, and may be 15 arranged at any desired angle with respect to the crib or carriage and at any desired elevation to suit the convenience of the infant.

Bridging the ring 26 is a band 38 of electric conducting material. The sides of this 20 band are spaced away from each other by a block of insulating material which is indicated by the numeral 39. To one side of the band is soldered or otherwise secured one end of an electric conductor 40, and 25 connected to an adjustable element 41 that passes through a threaded opening in the block 39 is a second electric conductor 42. The element 41 is in the nature of a screw and is therefore, of course, adjustable. The 30 end of the screw is arranged opposite the upper end of the rod 29, and by adjusting the screw so that the same contacts with the said rod the pressure of the spring 33 between the cap nut 32 and the stud or lug 34 may be 35 likewise adjusted. In this manner different quantities of milk may be arranged in the bottle 37 sufficient, however, to hold the rod 29 out of contacting engagement with the adjustable conductor 41. The ring 26 as well 40 as the rod 29 are of electric conducting material, and the conducting wires 40 and 42 are wrapped together in the usual manner and are suspended upon the bottle supporting device by elastic bands 43. These wires connect with a plug 44 to which is attached a 45 switch 45, the said switch engaging with the plug 46 having conductor wires 47 and 48 which lead to a source of electric energy 49 that is in circuit with a buzzer 50.

50 As stated, the weight of the milk in the bottle is designed to keep the conducting rod 29 out of engagement with the contact 41. As the baby consumes the milk the spring 33 will exert its influence on the rod 29 to bring 55 the same in engagement with the contact 41, when the current from the battery will pass through the contact and through the ring 26, thus completing the circuit through the buzzer 50. The sound of the buzzer will attract 60 attention to the nurse so that the bottle may

be removed and refilled if necessary, and consequently the infant will not be permitted to suck in air from the bottle so that danger of an attack of colic, common in such instances will be obviated.

65

It is, of course, apparent that by operating the switch the circuit may be cut off, and it will also be apparent that the electric wire may be removed if desired. In this last instance the bottle is resiliently supported and 70 may be sustained, as previously stated, at any desired adjustment for convenience of the infant.

The improvement contemplates means for supporting the bottle independent of the 75 alarm, and in Fig. 5 the suspending rod 51 to which the cage of the bottle is attached is not inclosed in the tubular casing 28, and is not spring influenced; the same being pivotally connected to a yoke 52 that is swiveled 80 on the lower face of a block 53 which is slideable on the horizontal rod 54. A binding element, in the nature of a thumb screw 56 holds the block adjusted on the rod. The rod 54 is connected to a block, similar to the 85 block 18, and this block is vertically adjustable on the vertical rod for the device. The block 57 has a threaded opening through which passes a binding element in the nature of a thumb screw 58 which frictionally contacts with the vertical supporting rod 59.

It is believed that the foregoing description, when taken in connection with the drawings fully set forth the details of construction and operative arrangement of 95 parts, and it is believed that the advantages of the improvement will present themselves to those skilled in the art to which such inventions appertain without further detailed description.

100

Having thus described the invention, what is claimed as new, is:—

A circuit closer comprising a ring adapted to be supported from a rod, a casing supported by the ring, a spring influenced rod 105 movable through the casing and having its lower end hooked to support a fluid containing bottle and designed to be moved outwardly of the casing against the pressure of the spring when the bottle is filled, bridging 110 members, forming one contact, mounted on the ring, a threaded core, forming the other contact, carried by but insulated from said bridging members, and an adjustable screw inserted in the core and adapted to make 115 contact with the rod when a predetermined amount of fluid is removed from the bottle.

In testimony whereof I affix my signature.

CHARLES H. MCNEIL.
